GRINDING WHEEL TOOL

Curvin E. Strausbaugh, Port Royal, S. C.

Application August 18, 1939, Serial No. 290,909

4 Claims. (Cl. 125—37)

The present invention relates to new and useful improvements in grinding wheel tools and has for its primary object to provide, in a manner as hereinafter set forth, a device of this character comprising novel means for expeditiously resurfacing and truing different kinds or types of wheels which have become worn from use.

Another very important object of the invention is to provide, in a hand tool comprising a plurality of toothed discs or cutters engageable with the wheel, novel means for adjusting or feeding said cutters relative to said wheel.

Other objects of the invention are to provide a grinding wheel tool of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a top plan view of a grinding wheel tool constructed in accordance with the present invention.

Figure 2 is a view in side elevation thereof.

Figure 3 is an end elevational view.

Figure 4 is a cross sectional view, taken substantially on the line 4—4 of Fig. 2.

Referring now to the drawing in detail, it will be seen that the embodiment of the invention which has been illustrated comprises a handle 1 of suitable material. Extending longitudinally into the handle 1 from the forward end thereof is a slot 2 providing spaced, parallel bifurcations 3. Extending longitudinally through the handle 1 is a bore 4 which communicates with the slot 2. Adjacent the bifurcations 3, the handle 1 is further provided with a transversely extending slot or opening 5 which communicates with the bore 4.

The free end portions of the bifurcations 3 have formed integrally therewith a pair of lugs or ears 6 the purpose of which will be presently set forth. Extending between the free end portions of the bifurcations 3 is a removable pin 7. A cotter pin 8 retains the pin 7 in position. The reference numeral 9 designates a plurality of toothed cutter discs which are mounted on the pin 7 between the bifurcations 3. Spacers 10 (see Fig. 3) separate pairs of the cutters 9.

Mounted for sliding adjustment between the

bifurcations 3 is a combination stop and guard 11 of suitable metal which is of substantially the shape shown to advantage in Fig. 2 of the drawing. Referring now to Fig. 4 of the drawing, it will be observed that the stop 11 has formed in its side edges notches or recesses 12 which slidably accommodate the bifurcations 3. Threadedly connected to the stop 11 is a rod 13 which extends slidably into the bore 4 in the handle 1. Threadedly mounted on the rod 13 and operable in the slot 5 of the handle 1 is an adjusting nut 14. It will be observed that the adjusting nut 14 is knurled to facilitate rotating same.

It is thought that the manner in which the tool is used will be readily apparent from a consideration of the foregoing. With the grinding wheel stationary, the ears 6 are placed on the usual rest of the frame of the grinding wheel and the adjacent end of the stop 11 is held against the outside edge of said rest. Through the medium of the nut 14, the stop 11 is then adjusted to permit the cutters 9 to be moved to the desired position closely adjacent the periphery of the grinding wheel. The grinding wheel is then rotated and the stop 11 is again adjusted in a manner to permit the cutters 9 to be gradually moved into contact with said wheel. The tool is then moved laterally back and forth across the periphery of the grinding wheel for resurfacing and truing same, proper adjustment or feeding of the tool being carried on during this operation through the medium of the nut 14.

It is believed that the many advantages of a grinding wheel tool constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A grinding wheel tool of the character described comprising a handle having a longitudinal bore therein and further having a transverse slot therein communicating with the bore, parallel bifurcations on one end of the handle, a plurality of toothed cutting discs rotatably mounted between said bifurcations, a stop slidably mounted between the bifurcations, a rod secured to said stop and extending slidably into the bore of the handle, and a nut threadedly mounted on said rod and operable in the slot in the handle for adjusting the stop longitudinally between the bifurcations.

2. A grinding wheel tool of the character described comprising a handle, bifurcations on one end of said handle, supporting ears integral with the free end portions of the bifurcations, said ears being engageable with a portion of the grinding machine, a plurality of cutter discs rotatably mounted between the bifurcations adjacent the ears, a stop slidably mounted between the bifurcations and engageable with the grinding machine, said stop being cooperable with the ears for positioning the cutter discs relative to the grinding wheel, and means for adjusting the stop longitudinally between the ears.
- 5
3. A grinding wheel tool of the character described comprising a handle, bifurcations on one end of said handle, supporting ears integral with the free end portions of the bifurcations, said ears being engageable with a portion of the grinding machine, a plurality of cutter discs rotatably mounted between the bifurcations adjacent the ears, a stop slidably mounted between the bifurcations and engageable with the grinding machine, said stop being cooperable with the ears for positioning the cutter discs relative to the grinding wheel, and means for adjusting the stop

- 25

longitudinally between the ears, the handle having a bore extending longitudinally therethrough, said means including a rod threadedly connected to the stop and extending slidably into the bore, and an adjusting nut threadedly mounted on the rod in the handle for shifting said rod longitudinally.

4. A grinding wheel tool of the character described comprising a handle having a bore extending longitudinally therethrough, bifurcations on one end of said handle, a plurality of cutter discs rotatably mounted between the free end portions of said bifurcations, a substantially arcuate stop slidably mounted between the bifurcations, said stop having notches therein slidably accommodating the bifurcations for mounting said stop therebetween, a rod connected to the stop and extending slidably into the bore, the handle further having a transversely extending slot therein communicating with the bore, and a nut threadedly mounted on the rod and operable in the slot for adjusting the stop longitudinally between the bifurcations.
